CLAIM

The ornamental vacuum cleaner nozzle, as shown and described.

DESCRIPTION

FIG. 1 is a perspective view of a vacuum cleaner nozzle showing our new design;

FIG. 2 is a top elevational view thereof;

FIG. 3 is a front elevational view thereof;

FIG. 4 is a rear elevational view thereof;

FIG. 5 is a side elevational view thereof; and,

FIG. 6 is a side elevational view of the opposite side of FIG. 5.

The detail shown in broken lines in FIG. 1 is for illustrative purposes only and forms no part of the claimed design.
